UNITED STATES PATENT OFFICE.

ARCÁNGEL PERRUSI, OF BUENOS AIRES, ARGENTINA.

METALLIC ROOFING.

1,330,493.

Specification of Letters Patent. Patented Feb. 10, 1920.

Application filed November 27, 1918. Serial No. 264,395.

To all whom it may concern:

Be it known that I, ARCÁNGEL PERRUSI, a citizen of the Argentine Republic, residing at No. 1767 Médanos St., Buenos Aires, Argentina, have invented certain new and useful Improvements in Metallic Roofing, of which the following is a specification.

The present invention refers to a new joint or coupling for metal sheets, corrugated or otherwise and has for its essential object the provision of a special rafter to which are fitted or attached the adjoining edges of the said sheets.

Another object of the present invention is to provide a rafter of the kind specified, which in construction is composed of the said sheets and serves as a girder and permits of the total suppression of the latter.

The invention may be applied without distinction to permanent or provisional constructions, and to roofs, walls, fences, etc., in which flat or corrugated metal sheets are employed.

The rafter in accordance with the present invention consists essentially of a metal plate bent to the shape of a U, having at the upper part flanges at right angles to its sides, and on the sides projecting ribs parallel to the said flanges.

In order that the invention may be clearly understood and readily employed, it has been represented by way of example, in several of its forms, in the attached drawings, in which:

Figure 1 is a view from above of two metal sheets joined by the rafter in accordance with the present invention.

Fig. 2 is a section of one of the said metal sheets.

Fig. 3 is a vertical cross-section of the intermediary rafter.

Fig. 4 shows an accessory piece which is employed in combination with the said rafter in joining two sheets.

Fig. 5 is a cross-section of the joint between two metal sheets in accordance with one of the forms of the invention.

Fig. 6 is a similar view illustrating another form of employing the rafter in order to join the edges of two corrugated sheets.

In all the figures mentioned, the same reference numbers indicate the same or corresponding parts.

With reference to these figures, 1 is a metal sheet having its longitudinal edges

turned up as indicated at 2 and having also longitudinal ribs 3. The intermediary piece is formed by a metal plate of appropriate length and weight bent to the shape of a U, 4 being the base and 5 the sides. On these 60 sides are ribs 6 and at the top of the U are flanges 7 which project outward and are substantially at right angles to the sides of the piece.

This rafter may be employed to join two 65 sheets in several different ways, as for example in the manner indicated in Figs. 1 to 4, by adjusting the sheets in such a manner that the longitudinal edges 2 of the adjoining sheets 1 rest on the side ribs 6 of 70 the rafter, and employing an additional piece 8 bent in the form of a C, as indicated at 9, which slides along the upper flanges 7 of the rafter in such a manner as to grip between the said flanges and the parts 9 of 75 the covering piece, the turned up portion of the edges of the sheets which it is required to join. In this manner the sheets may be joined without the use of nails or screws, absolutely avoiding percolation of 80 water through the joints, and considerably facilitating the setting up and taking down of the parts.

Fig. 6 illustrates a different form of the invention, in which the covering piece 8 is 85 suppressed and the sheets 1 are joined by one being made to overlap the other, the sheets resting upon the flanges 7 of the intermediary piece to which they are affixed by means of screws and bolts as shown at 10. 90

The adjustment of the sheets with respect to the rafters may differ from that shown in the drawings, without thereby departing from the scope of the invention, which is clearly determined in the clauses of the 95 claim which follow this specification.

In all the forms in which the invention may be employed, either in the case of roofs, or in the construction of walls, either permanent or temporary, girders of any kind may 100 be dispensed with, the rafters resting on the walls or being fixed in the foundations as required in either case.

Claim:

A waterproof metal roofing including, in 105 combination, a rafter formed of sheet metal and bent transversely throughout its length into a U-shaped configuration, flanges continuing at right angles from the upper portions of the sides of the rafters and project- 110

ing in opposite directions, outwardly extending ribs projecting at right angles from the sides of the rafter, the ribs being integral with the rafter and possessing a double thickness for reinforcing purposes, plates resting on the ribs and having upwardly curved edges and a slideable and removable

flanged retainer having its flat body portion resting on the flanges and its flanged edge portions engaged with the curved edges 10 of the plates on the ribs.

In testimony whereof I affix my signature.

ARCÁNGEL PERRUSI.
